UNITED STATES PATENT OFFICE.

ERASTUS WOODWARD, OF BOSTON, ASSIGNOR TO THE PENTUCKET VARIABLE STITCH SEWING MACHINE COMPANY, OF HAVERHILL, MASSACHUSETTS.

FEEDING DEVICE FOR SEWING-MACHINES.

SPECIFICATION forming part of Letters Patent No. 380,008, dated March 27, 1888.

Application filed June 3, 1886. Serial No. 204,001. (No model.)

To all whom it may concern:

Be it known that I, ERASTUS WOODWARD, of Boston, in the county of Suffolk and State of Massachusetts, have invented certain new and useful Improvements in Feeders for Sewing-Machines, of which the following is a specification.

My invention relates to work-feeding devices used in machines of the type shown in Letters Patent No. 316,927, granted to me and T. K. Keith, April 28, 1885, the feeding device shown in said patent being movable in any horizontal direction, so that it can carry the work in any direction under the needle and cause the stitches to form various designs, as shown and described in said patent, and in Letters Patent granted to me December 14, 1886, No. 354,499.

The object of the present invention is to so mount the feeder in its support that its serrated face will at all times, in the operation of the machine, have an extended bearing upon the work and be capable of conforming to inequalities in the thickness of the particular portion of the work on which it rests, thereby securing certainty in the movement of the work, and consequently in the position or character of the stitches.

I will now proceed to describe my invention, so that those skilled in the art may be able to make and use the same, the invention being particularly set forth in the claims hereto appended.

Of the drawings hereto annexed, and forming a part of this specification, Figure 1 represents a top plan view, Fig. 2 a side view, and Fig. 3 a vertical central sectional view, of a feeding device and its immediately-attached parts. Fig. 4 represents the head of a sewing-machine of the kind described and illustrated in the hereinbefore-mentioned Letters Patent with my feeder operatively attached thereto.

Similar letters of reference indicate similar parts in all of the figures.

My feeder is designed, as will be seen by reference to the Letters Patent hereinbefore mentioned, to operate on the upper surface of the goods to move them into various positions in order to form ornamental or embroidering stitches of various patterns or designs thereon.

In the present instance the feeder *a* is formed of a plate of metal, having its acting face or under surface roughened or provided with points in the usual manner, and provided with a hole or opening, *b*, through which the needle works. One edge of the opening *b* preferably has a V-shaped projection, *b'*, which bears on the work close to the needle *A*, and holds the work while herring-bone stitches extending substantially parallel with the sides of the said projections are being formed.

Ears *e* are formed on the sides of the feeder and project upward therefrom, and by means of these ears and pivot screws or pins *s* the feeder is pivoted to the ends and between the arms *c c* of a yoke, *y*, as shown in Fig. 1. Yoke *y* has a stud, *d*, projecting rearwardly therefrom, by means of which the yoke is pivoted to the shank or support *e'*, so as to rock or turn therein, said shank being secured to a plate, *B*, which is free to rise and fall in guides on an arm, *C*, attached to a longitudinally-movable rock-shaft, *D*, whereby the desired feed movements are given to the feeder, as shown in Fig. 4, and fully shown and described in the above-named Letters Patent. The pivotal connection of the yoke *y* in the support *e'* being at right angles to the pivotal connection of the feeder with the yoke, it follows that the nature of the connection of the feeder with the support *e'* will be that of a universal or gimbal joint, so that the feeder will always be held with its serrated or roughened face pressed uniformly on all portions of the work immediately under the feeder, and will be capable of being inclined as may be required to cause it to conform to folds or plaits or the inequalities in the thickness of the work, thus securing certainty in the movement of the goods and exactness in the position or character of the stitches.

It is obvious that the character of the connection between the feeder and the support *e'* does not affect such movements of the latter as are designed to operate the former for the purpose of feeding or moving the goods.

Having thus described my invention, I claim—

1. The combination of the feeder, the support *e'*, and a universal or gimbal joint connection between the feeder and the support,

whereby the feeder may be variously inclined with respect to the support to conform to the work under it, substantially as set forth.

2. The combination of the feeder, the yoke 5 having a pivotal connection with the feeder, and the support e' , having a pivotal connection with the yoke at right angles to the pivotal connection of the yoke with the feeder, as set forth.

to 3. The combination, with the feeder a , pro-

vided with the ears e , of the yoke y , having the arms $c c$, pivot screws or pins s , stud d , and support e' , substantially as set forth.

In testimony whereof I have signed my name to this specification, in the presence of two sub- 15 scribing witnesses, this 1st day of June, 1886.

ERASTUS WOODWARD.
